UNITED STATES PATENT OFFICE

2,091,322

PRINTING UNIT

Abel Kluge and Eneval Kluge, St. Paul, Minn., assignors to Brandtjen and Kluge, Inc., St. Paul, Minn., a corporation of Minnesota

Application December 30, 1932, Serial No. 649,567
Renewed February 8, 1937

11 Claims. (Cl. 101—287)

Our invention relates to improvements in printing units in which sheet feeding and delivering mechanisms are incorporated.

Heretofore, in the field of hand fed platen presses and, particularly, presses of the so-called Gordon type, it has been customary to attach thereto, in various ways, feeding and delivering mechanisms of one form or another such, for example, as is shown in Patent Nos. 1,145,405 and 10 1,472,856. In converting such presses by attaching such mechanisms thereto in order that they may be fed automatically, as well as by hand, comparatively good results have been attained. But, with the modern trend, wherein the tendency is to eliminate hand feeding at every opportunity and to increase production through the use of automatic facilities, such composite structures are not wholly acceptable. That is to say, there is more to be desired in a structure which, almost exclusively, is to be operated automatically. This gives rise to various needs and particularly to the need of a structure of a unitary design and construction by which printing of highest excellence may be turned out at high speed.

It is an object of our present invention to supply an improved printing unit of the present character in which relatively short throws of the bed permit of high operating speeds, and in which the associated elements are designed and coordinated to provide a compact unitary organization of high and lasting efficiency, capable of smooth operation at sustained high speed.

Another object of our invention is to provide a construction, as above, wherein the different elements in the power train, which operate the various moving parts of the structure, are devised and associated in a manner making for simplicity and durability.

40 A further object of the invention is to provide an automatic printing unit of the bed and platen type in which control of the sheets, from the stock magazine to the delivery pile, is at all times maintained.

45 A further object of the invention is to provide in a printing unit of the present nature, grippers which hold the printed sheet in place on the opening platen and which, in their receding movement from the platen, are coordinated with the 50 movements of the delivery grips and feed grips to free the printed sheet to the former and to keep clear of the latter and the fresh sheet carried thereby.

An additional object of the invention is to support a printing unit of the present nature having

registering means, adjustable while the platen is in motion, for shifting a fed sheet into selected position on the platen and having platen grippers for holding the printed sheet flatly against the opening platen to keep said sheet from curling and to keep it from being otherwise displaced from such selected position on the platen as by the rapid movement of said platen in opening, or by the retreating movement of the register means and, further, having delivery grips for grasping the printed sheet, at predetermined localities thereon, in the said selected position of said sheet on the platen.

Another object of the invention resides in incorporating in a printing unit of the present kind, a trip mechanism adapted to be actuated upon failure of the feed grips to take a sheet, such mechanism including linkage for turning the eccentric backshaft of the bed to throw-off the impression, said linkage having a pivot, between links, normally axially held in position coinciding with the axis about which the bed rocks and adapted, in such relation of said pivot, to secure said eccentric shaft against turning as the bed rocks back and forth.

An object of the invention is to supply a printing unit of the present nature, in which reciprocating linkage, operated through the power train, is employed to operate the sheet advancing mechanism of the swingable stock magazine and is provided, between links, with a swiveling coupling axially aligned with the axis on which the magazine swings.

Another object of the invention is to provide, through the power train of the unit, coordinated movements of the delivery grips and the pile gauge which controls the lowering of the delivery table, whereby the gauge is shifted into a position so as not to interfere with the proper piling of a sheet as it drops from the delivery grips.

An additional object of the invention is to provide a novel roller carriage construction which is reciprocated through balanced driving mechanism designed to minimize wear and strains on the parts.

Another object of the invention is to provide for the simplified and effective actuation of the platen rocker lock.

A feature of the invention resides in interposing an ink fountain between the ink plate and the position occupied by a form on the bed, and in oscillating the ink fountain to apply ink to the inking rollers only, as they pass from the form toward the ink plate.

Another feature of the invention resides in the

5

40

45

50

55

novel and effective association of the oscillating fountain with the throw-off mechanism of the unit so that the fountain will be shifted into and held in inoperative position when the impression 5 is thrown off.

A further object of the invention is to provide, in connection with the roller carriage, a frame for form roller rider rolls, which frame is swingable to give access to the form rollers at the front 10 of the carriage.

Another object of the invention is to provide for the ready removal of the form rollers from the carriage, and for the ready adjustment of said rollers in the carriage, whereby, in a single guided 15 movement, each form roller may be shifted toward or from the plane of the form and inking plate and, simultaneously, toward or from the periphery of its respective rider roll.

A feature of the invention resides in swinging 20 the inking plate out of the inking plane to lend access thereto and to the form rollers at the rear of the roller carriage.

A still further object of the invention is to provide for the intermittent oscillation of the 25 inking plate, to present the same in different angular relations with respect to the form, whereby uniformity in the distribution of ink is promoted.

With the foregoing and other objects in view, 30 which will appear in the following description, the invention resides in the novel combination and arrangement of parts and in the details of construction hereinafter described and claimed.

In the drawings, Figs. 1 and 2 are perspective 35 views of a printing unit embodying our invention; Fig. 3 is an elevational view of the unit as seen from the left side thereof; Fig. 4 is a rear elevational view thereof; Figs. 5 and 6 are vertical, central sectional views of the unit taken from 40 front to rear thereof in opposite directions; Fig. 7 is a vertical sectional view taken as on the line 7—7 of Fig. 5; Fig. 8 is a detail view illustrating, particularly, the gearing and cam assembly at 45 the right side of the unit; Fig. 9 is a detail view in vertical section of the cam assembly; Figs. 10 and 11 are detail views illustrating the platen rocker lock, Fig. 11 being a fragmentary rear elevational view and Fig. 10 a vertical sectional view taken on the line 10—10 of Fig. 11; Fig. 12 is a 50 vertical, central sectional view taken through the bed of the unit, the same illustrating the construction and relative arrangements of the roller carriage rails, the oscillating ink fountain, the swingable ink plate, the carriage blocks and the 55 form rollers and distributing rider rollers carried thereby; Fig. 13 is a detail view in section taken as on the line 13—13 of Fig. 12; Fig. 14 is a perspective view illustrating one of the carriage blocks and also showing the construction of the 60 adjustable cup bearings for the form rollers; Fig. 15 is a sectional view in detail, the same being taken as on the line 15—15 of Fig. 12; Fig. 16 is a detail perspective view of one of the cup bearings for the form rollers; Figs. 17, 18, 19 65 and 20 are diagrammatic views illustrating the action of the mechanisms employed to oscillate the ink fountain and to rotate the fountain roll; Figs. 21, 22 and 23 are elevational views illustrating details in the construction of the delivery table lowering mechanism, Figs. 21 and 22 being taken from position as at the left of the printing unit and Fig. 23 as from the front thereof; Figs. 24 and 25 are also detail views, said 70 views showing the platen and the side register gauge therefor with its mechanism for adjust-

ing the thrust of said gauge while the platen is moving, and Figs. 26, 27, and 28 are additional detail views showing the oscillating inking plate, its swingable mounting and the means employed for oscillating said plate, Fig. 26 being a front elevational view, Fig. 27 a sectional view taken on the line 27—27 of Fig. 26, and Fig. 28 a view similar to Fig. 27 showing the parts of the plate oscillating mechanism in positions differing from those shown in Fig. 27.

Reference being had to the drawings, wherein similar parts throughout the several views are designated by similar reference characters, it will be noted that in the printing unit illustrated as an embodiment of our invention, the framework of said unit includes right and left side frames 30, 31 connected by cross stays 32. A crankshaft 33 journaled in the side frames 30, 31 carries a fly wheel 34 at one end thereof and to this is keyed a pinion 35 (Figs. 1 and 8), which meshes with a gear cam wheel 36 fixed to a shaft 37 journaled in said side frames 30, 31. Trunnioned in the side frames 30, 31 is a platen rocker 38 carrying a platen 39. Secured to a trunnion 40 (Fig. 8) of said platen rocker 38 is a 25 rocker arm 41 having a cam roller 42 thereon which travels in the cam 43 of the gear cam wheel 36, said rocker arm 41 serving to oscillate said platen rocker 38 and the platen 39 carried thereby. Back of the side frames 30, 31 is a 30 bed 44 having a form receiving recess 45 therein and having legs 46 pivoted on a bed shaft 47 mounted at its ends in the lower rear portions of the side frames 30, 31. Journaled in ears 48 projecting rearwardly from the bed 44 is a back 35 shaft 49 to the ends of which are connected side arms 50, 51, the former being connected with a crank wheel 52 on the shaft 37 and the latter with the gear cam wheel 36 also on said shaft 31. Power applied to the crank shaft 33, as 40 through a pulley 53 (Fig. 4) thereon, causes the platen 39 to tip back and forth from open position (Fig. 6) to impression position (Fig. 3) and causes a relative movement of the bed 44, bringing a form therein against the platen 39 in its 45 impression position and substantially retracting the bed 44 from the platen 39 in the open position of the latter.

Rails 54 secured to the sides of the bed 44 guide carriage blocks 55 up and down thereon. These 50 blocks 55 support inking rollers 56 which in their reciprocating cycle, contact with a form in the bed 44 and with an inking plate 57 between the rails 54 and also with the fountain roll 58 of an oscillating ink fountain 59 disposed between said 55 bed and inking plate. The carriage blocks 55 are reciprocated in unison by similar mechanisms at either side of the unit, which include bell-crank 60 keyed to the opposite ends of a unit master shaft 61 journaled in the side frames 30, 60 61, and which further include rods 62 and links 63, the rods 62 connecting the bed with said bell cranks 60 and the links 63 connecting said bell cranks with said blocks 55. Due to the arrangement of the bell cranks 60, as shown, the connections between them and said links 63 are constantly disposed substantially in the reciprocal plane of the carriage blocks 55, the result being that forces acting on the carriage blocks 55, through links 63, are at all times exerted in directions substantially parallel with the rails 54 upon which said blocks ride. This feature, is shown in Figs. 3 and 5, where the blocks occupy extreme 65 positions and the links 63, in both positions of said blocks, occupy positions substantially para- 70 75

leling the rails 54. With said links 63 thus disposed at all times with respect to the rails 54, it will be readily understood that lateral thrusts of the carriage blocks 55 against their rails are practically eliminated and that said blocks will move freely up and down on said rails without binding.

Counterbalancing the weight of the roller carriage blocks 55 and the rollers 56 carried thereby, is a compression spring 64 (Fig. 6). This spring 10 encircles a rod 65 pivotally connected at its forward end to a cam 66 on the unit master shaft 61 and slidably mounted at its rear portion in a bracket 67 secured to a cross stay 32 between the side frames 30 and 31. The forward end of the 15 spring 64 abuts against a collar 68 on rod 65 while the rear end of said spring abuts against the bracket 67. The cam 66, not only performs the function of a cam, as later will be described, but also constitutes an arm for resisting, through 20 spring 64, the rotation of shaft 61 in a direction to lower the carriage blocks 55, the strength of said spring being such as to substantially balance the carriage blocks 55 and the inking rollers carried thereby. In this construction, the carriage 25 blocks 55 with their rollers 56 are easily moved up and down the rails 54 without strain or undue wear upon the parts.

The cam 66, last above mentioned, actuates a rocker lock 69 (Figs. 10 and 11), hinged on a shaft 30 70 mounted at its ends in the side frames 30, 31. This rocker lock includes a pair of arms 71 formed with bosses 72 journaled on said shaft 70, said arms being connected through reinforcing tie members 73. Depending from one of the 35 bosses 72 is an arm 74 having a roller 75 at the lower end thereof which rides the cam 66 on shaft 61, said roller being held against the face of said cam by means of an expansion spring 76. This spring encircles a rod 77, which is attached 40 at its forward end to a lug 78 fastened to an arm 71 of the rocker lock, said rod being slidably forth and back through an aperture in a lug 79 fastened to the side frame 31. The forward end of said expansion spring 76 abuts against said lug 79, 45 while the rear end thereof abuts against a collar 80 on the rod 77. The joint action of the cam 66 and spring 76 causes the rocker lock 69 to swing forth and back and to dwell during certain periods at the extremities of its movement. Said rocker 50 lock 69 cooperates with a locking extension 81 on the platen rocker 38. In the impression position of the platen, shoulders 82 (Figs. 10 and 11) on said locking extension engage abutments 83 on cross stay 32, said extension having abutments 84 55 thereon which, in turn, are engaged by the tips of the arms 71 of the rocker lock. Thus, the locking extension 81 is held locked against movement in one direction by the framework of the unit and against movement in the opposite direction by the rocker lock 69. With the locking extension 81 held in this manner, the platen 39 on rocker 38 is rigidly held in the proper position to receive the impression at the appropriate time in the cycle of relative movement of the platen and bed. Following the impression period and before 60 the platen begins to open, the rocker lock 69 is caused to swing forward, against the action of spring 76, out of its extension engaging position into inoperative position (Figs. 5 and 6) and is 65 caused to remain in such inoperative position until the platen returns to impression position, whereupon spring 76 is permitted to act and thus again engage the arms 71 thereof with the abutments 84 of the platen rocker extension 81.

75 Provision is made for throwing off the unit or,

in other words, for shortening the normal forward throw of the bed 44 and thereby preventing the form in the bed from contacting with the platen 39 in its impression position. To this end, the back-shaft 49 is formed at its extremities with 5 eccentric studs 85 (dotted lines, Figs. 17-20) to which the rear ends of the side arms 59 are pivotally connected. Secured to the back-shaft 49 for rocking the same, is an arm 86 (Figs. 3 and 7) having pivoted thereto a depending link 87. At 10 its lower end, this link 87 is connected through a pivot pin 88 with the forward end of an arm 89 (Figs. 2 and 3), the rearward end of which is pivoted to an upright bracket 90 secured to a foot of the side frame 31. Said arm 89 is normally held against pivoting on the bracket 90 and in position, wherein the axis of the pivot pin 88 coincides with the axis of the bed shaft 47. In this relation of said parts, the back shaft 49 is held against rotation as the bed 44 rocks back and forth and in such angular position in its bearings that the eccentric studs 85 are properly disposed to cause the form in the bed to contact with the platen 39 in the impression positions of bed and platen. The means for holding the arm 89 in its normal position (Fig. 2) consists of a suspension link 91, jointed medially as at 92. This suspension link 91 is pivoted at its lower end to the arm 89 by means of the pivot pin 88 through which said arm is connected to the depending link 87, the upper end of said suspension link 91 being pivoted to the tip of the upright bracket 90. Through said suspension link 91, the forward end of the pivoted arm 89 is elevated to 15 thrust the link 87 upwardly and thus rock the arm 86 and turn the back shaft 49 sufficiently to prevent the bed from closing against the platen. Operating to break the jointed suspension link 91, and thus swing the arm 89, is a hand lever 93 pivoted between its extremities to a bracket 94 on 20 the side frame 31, the lower end of said lever 93 being connected by means of a tie bar 95 with an arm 96 issuing from the upper member of the jointed link 91. Upon swinging the upper end of the hand lever 93 rearwardly, the link 91 is broken 25 at the joint 92 therein and the train of parts, consisting of the pivoted arm 89, depending link 87 and rock arm 86, is actuated to rock the back shaft 49 and throw off the impression. The impression is thrown on again by swinging the hand 30 lever 93 back and thus restoring the back shaft 49 to its normal position. As the jointed suspension link 91 reassumes its extended position, the axis at the joint 92 thereof passes slightly past center at which point the lower extremity of the 35 upper member of said link engages a stop lug 97 on the pivoted arm 89. In this relation of parts, the jointed link 91 is locked against being broken, except through a pull on the tie-bar 95, the pivoted arm 89 being thus rigidly held against 40 pivotal movement and the back shaft 49, in turn, firmly held against rotation in the rocking bed. The hand lever 93 is not only operated by hand, but is also operated automatically, as will later appear, for the purpose of throwing off the impression when the automatic sheet feeding mechanism, hereinafter described, fails to grasp a sheet and for the purpose of throwing on the impression when said feeding mechanism again takes a sheet.

The guide rails 54 for the ink roller carriage blocks 55 consist of bars suitably secured flatwise to the sides of the bed 44, each of the bars being beveled at both edges to form opposed V-shaped ways 98.

The carriage blocks 55, constituting a roller 75

carriage, ride up and down on said guide rails 54 and in their reciprocating cycle bring the composition form rollers 56 into contact with a form in the bed 44 and with the fountain roll 58 of the oscillating inking fountain 59 carried by said rails 54 above the bed, and also bring said composition rollers 56 into contact with the inking plate 57 carried by said rails 54 above said inking fountain 59. On the upward stroke of the carriage blocks 55 the ink rollers 56 engage the then projected fountain roll 58. In the final stage of said upward stroke of said carriage blocks, and also during the initial stage of their downward stroke, the ink rollers 56 contact with the inking plate 57 effecting a distribution of ink thereon and on said rollers 56. As the carriage blocks 55 descend and pass the form in the bed 44, the ink rollers 56 contact with and ink the form.

The carriage blocks 55 are elongated structures, each including a web-like body and front and rear bearing 99 (Fig. 14), which correspond with and ride the opposed V-shaped ways 98 of its respective carriage rail 54. Each carriage block 55 further includes a forwardly projecting frame plate 100, the two frame plates of the two blocks serving to support the form rollers 56. Hinged frames 101 (Fig. 12), one for each plate 100, support link distributing rolls 102, which ride the form rollers 56. Each hinged frame is of a bar-like construction pivoted at one extremity to the lower end of its respective frame plate 100 and provided at its other extremity with a locking head 104. Normally these hinged frames 101 are closed upon the frame plates 100 of the carriage blocks 55, the head 104 of each hinged frame being releasably engaged by a latch 105 pivoted at the upper end of its respective frame plate 100.

The rider rolls 102 (Figs. 7 and 13) are of the vibrating type, the threaded ends of the shafts 106 thereof being threaded in one of the hinged frames 101 in bosses 107, while the opposite ends of said shafts are journaled in the other hinged frame 101 in bosses 108. Said shafts 106, at said latter ends thereof, are provided with gears 109 meshing with idler gears 110 mounted on the frame plate 100 of the corresponding carriage block 55, said idler gears 110 being also in mesh with a rack bar 111 secured to the rail 54 upon which said block rides. The bosses 107, 108 on 50 the hinged frames 101 enter guiding recesses 112 (Figs. 12 and 14) in the frame plates 100 when said frames 101 are closed upon said frame plates with the result that the vibrating rider rolls 102 always have the same relative disposition in the 55 roller carriage when the hinged frames 101 are latched in place. The four composition form rollers 56 are arranged in pairs, the two rollers of one pair being adapted to be engaged by one of the vibrating distributor rolls 102 and the two rollers of the other pair being adapted to be engaged by the other vibrating distributor roll. All of said form rollers 56 are adapted to engage the inking plate 57 and the form in the bed 44, said rollers 56 being adjustably and 60 movably mounted on the frame plates 100 of the carriage blocks 55, the mode of mounting being the same in each instance. Referring to Figs. 12 and 14 and to the companion views on the same sheet, it will be seen that each inking roller 56 has roller bearings 113 secured to the opposite ends of its shaft 114. These roller bearings 113 are removably seated in cup bearings 115, each of which comprises a disk-like head 116 and a flange 117, semi-circular in form, issuing from 75 said head. On this head 116, at the side thereof

opposite the flange 117, is a curved rib 118, which fits in a curved groove 119 (Fig. 14) in one of the frame plates 100, said rib 118 and head 116 being formed with a threaded bore 120 to receive the threaded end of a fastening bolt 121 (Fig. 15) passing through a curved slot 122 formed in the frame plate 100 and communicating with the curved groove 119 in which the rib 118 is disposed. With the cup bearing 115 secured in place by its fastening bolt 121, the lower portion of the flange 117 slightly underreaches the roller bearing 113 placed therein, said flange in conjunction with a keeper 123 serving firmly to hold the roller bearing 113 in place. Said keeper 123 consists of a pin with a right angular bend therein one reach of the pin constituting a stem 124 which is slidably and rotatably mounted in a bore 125 in the head 116, the other reach of said pin constituting a finger 126 adapted to overreach the roller bearing 113 in cup bearing 115. A spring 127 acting on the stem 124 of the keeper causes the finger 126 to engage said roller bearing 113 yieldingly, said spring being interposed between the head 116 of the cup bearing and a pintle 128 passing through said stem 124 of the keeper 123. The head 116 is notched as at 129 (Fig. 16) to receive the finger 126 and thus allow it to engage and hold the roller bearing 113 seated in the cup bearing 115. At one side of this recess 129, the head 116 is machined to form a cam surface 130 upon which the finger 126 rides, when it is turned (Figs. 12 and 14) to free the roller bearing 113. In thus turning said finger 126, the cooperation thereof with said cam surface 130 results in readily sliding the stem 124 in the head 116 against the action of the keeper spring 127.

The curved grooves 119 for the companion cup bearings 115 of each pair of inking form rollers 56 are oppositely disposed, as shown in Fig. 14 and provide for adjustments of said cup bearings, whereby the form rollers 56 carried thereby may be shifted toward or from their respective ink distributing roller 102 and the plane common to the inking plate 57 and the form. These 40 adjustments are readily made to compensate for expansion and contraction in the form rollers 56, the ease of adjustment being facilitated due to the form and arrangement of the grooves 119, whereby the movement of an inking roller 56 50 toward its respective distributor roll 102 is effected simultaneously with a corresponding appropriate movement of such inking roller 56 toward the plane of the inking plate 57.

In addition to the vibrating rider rolls 102, the hinged frames 101 carry idler distributing rollers 131, 132 (Figs. 12 and 13), which ride certain of the form rollers 56. Roll 131 is journaled at its ends in pins 133 slidably mounted in bearings 134 secured to the hinged frame bars 101. These 60 bearings are so located on said frame bars 101 that the roller 131 lies between the lower roller of the upper pair of inking rollers 56 and the upper roller of the lower pair of inking rollers 56, when the hinged frame bars 101 are closed upon the frame plates 100. Said distributing roll 131, in such position, contacts yieldingly with said inking rollers, due to the action of expansion springs 135 which encircle the pins 133 and react against the bearings 134. Distributing roll 132 70 is arranged to engage the uppermost inking roller 56 and is journaled at its ends in clips 136 pivoted to the hinged frame arms 101 on clamping screws 137, which are released to permit of the 75

adjustment of said roller 132 and thereafter tightened to secure it in adjusted position.

In providing the upper rider roll 102 for the two form rollers 56 of the upper pair thereof 5 and the lower rider roll 102 for the two form rollers 56 of the lower pair, and in further providing the rider roll 131 for the lower form roller of the upper pair and for the upper form roller of the lower pair, the ink on said form rollers is effectively broken up, without interruption, through the entire train thereof.

In mounting the distributing rider rolls 102, 131 and 132 on the hinged frame arms 101, said rollers are easily swung forwardly away from the 15 form rollers 56 to facilitate the cleaning of all of said rollers. In further facilitating the cleansing of the inking rollers, the inking plate 57 is adapted to be swung rearwardly from its normal position (Fig. 6) into a retracted position such 20 as that shown in Fig. 12 and thus give access to the form rollers 56 from the rear as well as from the front.

The oscillating ink fountain (Fig. 12), indicated in its entirety at 59, includes end frame members 138 and the fountain feed roll 58 journaled at 25 its ends in said end frame members 138. This ink fountain 59 further includes a back wall 139, a plate 140 secured along its upper edge to said wall 139, and thumb screws 141 threaded 30 in said wall for holding the lower marginal portion of said plate 140 more or less closely positioned with respect to the fountain feed roll 58. The end frame members 138 are secured to brackets 142 pivoted on studs 143 threaded in the guide 35 rails 54.

A horizontally disposed U-shaped extension 144 (Fig. 4) is attached to the ink fountain 59, one branch of said extension being suitably secured to an end wall 138 of said fountain. A leg 145 secured to said extension and extending rearwardly therefrom and thence downwardly is supplied at its lower extremity with a roller 146 which bears upon a track 147 (Fig. 3). This track 147 is pivoted at its forward end to the side arm 50 at the left side of the unit, said track at the rear end thereof being beveled as at 148, the beveled portion resting upon a pin 149 mounted on a cap piece 150 secured to the end of the back shaft 49. Through said side arm 50 and track 50 147, the inking fountain 59 is oscillated and normally caused to swing forward and backward, whereby the fountain feed roll 58 occupies position for inking the form rollers 56 during the upward movement of said rollers, but is otherwise disposed in a retracted position to avoid contact with said inking rollers 56. This oscillation of 55 the ink fountain, through leg 145, is effected by the angular movement of the side arm 50 combined with the angular movement of the track 147 relative to said side arm. Referring to Figs. 17 to 20 inclusive, which illustrate diagrammatically various relative positions assumed by the ink fountain 59, form rollers 56, side arm 50 and track 147, it will be observed that, as the form 60 rollers 56 ascend toward the fountain feed roll 58, the side arm 50 elevates the forward end of the track 147 and at the same time causes the elevation of the rear end of said track by sliding the beveled portion 148 thereof upon the bearing pin 149. By reason of said compound movements of the track 147, said track is elevated sufficiently 65 to cause the rocking of the ink fountain 59 into a forwardly projected position in which the fountain feed roll 58 engages the ascending form rollers 56. As said form rollers 56 descend, the

change in angularity of the side arm 50 lowers the forward end of track 147 and simultaneously slides the beveled rear portion 148 thereof forwardly upon the bearing pin 149, such movement of said parts resulting in the lowering of the 5 track 147 sufficiently to allow the ink fountain 59 to swing backward and thereby retract the fountain feed roll 58 in time to avoid engagement with the descending form rollers 56.

The normal oscillation of the ink fountain 59, above described, is interrupted when the throw-off mechanism of the unit is operated to shorten the forward throw of the bed and prevent the taking of an impression. In this connection and having reference to Figs. 3 and 18, it will be seen 10 that the ink fountain 59 will be retracted upon a counter-clockwise movement of the back shaft 49 as a consequence of the upward throw-off 15 thrust of the link 87. Upon such rotation of the back shaft 49 the cap 150, which is secured thereto, turns with the said shaft and as a result moves the bearing pin 149 rearwardly beneath the beveled portion 148 of the track 147, thus lowering said track. The fountain 59, supported by the track, is thereby caused to be retracted, if not 20 then so disposed, and to remain in retracted position, wherein the fountain feed roll 58 clears 25 the form rollers 56.

The fountain feed roll 58 is rotated step by step to present freshly inked portions thereof to 30 the form rollers 56 by mechanism, best seen in Figs. 2, 4 and 7, which includes a drive shaft 151 journaled in the branches of the U-shaped fountain extension 144. Secured to this drive shaft 151 is a gear 152 which meshes with a gear 153 35 on the fountain roller shaft 154. A ratchet wheel 155 also secured to said drive shaft 151 is turned by means of a pawl 156 carried on one arm of a bell crank 157 rockably mounted on said driving shaft 151, the other end of said bell crank 40 being connected through a link 158 with the side arm 50 at the left side of the machine, said link serving to impart a rocking movement to said bell crank 157. To provide for the turning of the fountain drive shaft 154 more or less each 45 time the bell crank 157 is actuated, we employ a shroud 159 consisting of a disk rockably mounted on the drive shaft 151, said disk having an offset cam surface 160 with which the pawl 156 50 may be engaged to prevent its engagement with the teeth of the ratchet 155 during a part of the rocking movement of the bell crank 157. This shroud 159 is adjustably held in various selected 55 positions by means of a brace 161 which is pivotally secured at its lower end to the fountain extension 144 and slotted at its upper portion to pivotally and slidably receive a clamping bolt 162 carried by an arm 163 projecting from the disk-like body of the shroud 159. With said shroud 159 positioned in selected angular relation on 60 the shaft 151 and held in such position by the brace 161, the extent of rotation of the fountain roller 58 to accord with any particular requirement is secured. A hand wheel 164 on shaft 151 65 is supplied for manually turning the fountain roller 58 at such time as may be desired.

The inking plate 57, which is rectangular in form, is mounted on a back-frame 165 of similar form, said back-frame presenting a supporting surface against which the back of said plate 57 70 bears (Fig. 12). This back-frame 165 is hingedly supported upon the rails 54, ears 166, provided at the lower corners of said back-frame, being pivoted on studs 167 threaded into said rails. A prop 168, depending from a shaft 169 journaled 75

in ears on the back-frame 165, has a footing, normally, on the upper end of a brace 170 (Figs. 3 and 12) issuing upwardly and rearwardly from the bed 44. Through the brace 170, prop 168 and back-frame 165, the inking plate 57 is releasably held in operative position, the back-frame 165 occupying a position with the upper margin thereof abutting front stops 171 secured to the rails 54.

10 The inking plate 57 oscillates on the back-plate 165, the former having a central boss 172 (Fig. 12) journaled in a central bearing 173 formed on the latter. Mechanism, now to be described, automatically swings the inking plate 57 angularly from one position to another and back again, whereby, upon one cycle of the form rollers 56, said inking plate will occupy one position angularly of said form rollers and, upon the next cycle, will occupy another position angularly of said rollers, the shifting of the inking plate back and forth from one position to the other causing the ink on the rollers 56 and plate 57 to be effectively broken up and distributed thereon. Disposed between the rail 54 and the adjacent ear 166 of the back-frame 165, at the right side of the printing unit, is a cam 174 (Figs. 26 and 27) and a ratchet wheel 175 axially interconnected therewith, said cam and ratchet wheel being mounted to turn on the stud 167 supporting said ear 166. Cooperating with the ratchet wheel 175 is a pawl 176, the same being pivoted on the adjacent end frame 138 of the oscillating ink fountain 59. The cam 174 has alternating high and low portions, the teeth in the ratchet wheel 35 175 being the same in number as said portions of said cam. A thrust-rod 177, guided in a bracket 178 issuing from the back-plate 165, is connected at its upper end through a lug 179 with the upper right hand corner of the inking plate 57, the lower end of said thrust rod 177 being equipped 40 with a cam follower 180 which rides the cam 174. As previously explained, the oscillating ink fountain 59 is swung forward on each cycle of the form rollers 56 to bring the fountain roll 58 in contact with said form rollers 56 as the latter, in their ascent, approach the inking plate 57. Such forward swing of the inking fountain, causes the pawl 176 to turn the ratchet wheel 175 and also the cam 174 with which said ratchet 45 wheel is connected. Upon each step of the cam 174, the inking plate 57 is swung into one or the other of the two positions indicated in Fig. 26, said plate being caused to take the position shown in solid lines, when a high portion of the cam 174 comes into play and being caused to take the position shown in dotted lines when a low portion of said cam comes into play. The shifting of the inking plate 57 into said solid line position is accomplished by the co-action of a 50 high portion of the cam 174 and the thrust-rod 177, while the shifting of said plate, into said dotted line position, is accomplished by means of a spring 181 stretched between the lug 179 on said inking plate 57 and the guide bracket 178 on the back-plate 165, such spring serving yieldingly to keep the cam follower 180 in contact with the cam 174.

The platen 39 is equipped with mechanism for side registering a sheet thereon. This mechanism (Figs. 24, 25, 5 and 1) includes a rod 182 mounted to slide lengthwise along the lower edge of the platen 39 in bearings 183 and 184 secured to the platen, said rod being feathered in bearing 183, as shown. A roller 185 journaled on the 70 end of said side register rod 182, at the right

side of the platen, rolls up and down along an arcuate rail 186 as the platen 39 opens and closes, said roller 185 being yieldingly held against said rail 186 by means of an expansion spring 187 coiled about said rod 182 between the bearing 184 therefor and a thrust collar 188 thereon. The rail 186 is pivotally mounted medially thereof on a stud 189 (Fig. 5) projecting from the gear housing 190 and may be swung from one of its extreme positions shown in Fig. 24 to the other of its extreme positions shown in Fig. 25. For adjusting the rail 186 on its stud 189 and securing the same in its various adjusted positions, we provide an extension 191 which is rigidly bolted to the upper end of said rail and which is formed with a slotted head 192. A set bolt 193, threaded in the gear housing 190 and received in the slot of said head 192 is employed to releasably clamp the extension 191 against the gear housing and rigidly hold the rail in the desired position of 20 adjustment. A push-pull adjusting screw 194 journaled in a bearing 195 pivoted to the gear housing 190 is threaded in a nut (not shown) pivoted on the rail extension 191. This adjusting screw 194 is manipulated to secure roughly the 25 desired adjustment of the rail 186 as a preliminary measure and is further manipulated, during the operation of the printing unit, to secure finer adjustments of said rail. A right register gauge 196 of the construction shown in Fig. 24 or a left register gauge 196, as shown in Fig. 25, may be employed by mounting the same on an adjustable block 197 on rod 182, or the well known type of swinging tongue may be employed and operated through said rod 182 for engaging a 30 sheet on the platen and shifting it into register. For left register, the gauge 196 and rail 186 occupy positions, for example, as shown in Fig. 24, while for right register they occupy positions, for example, as shown in Fig. 25, the position of the 40 rail 186, in either case, being readily adjusted through the adjusting screw 194 during the operation of the printing unit, as above indicated.

Mounted on the unit master shaft 61 at the right side of the unit is a cam assembly (Figs. 45 1, 8 and 9) consisting of a sleeve 198 journaled on said shaft and of cams 200, 201, 202 and 203 all keyed to said sleeve. This cam assembly is driven from the gear cam wheel 36 through a reduction idler consisting of a large gear 204 and 50 a smaller gear 205, the former being in mesh with the teeth of the gear cam wheel 36 and the latter in mesh with a gear portion 206 formed on the cam 200.

Power is derived through said cam assembly 55 for driving the moving parts of a stock feeding magazine A, a sheet feeding mechanism B and a sheet delivery mechanism C.

The stock feeding magazine A is generally of the construction disclosed in Letters Patent of 60 the United States Nos. 1,693,936 and 1,694,015, which matured from applications filed by us. This magazine A (Figs. 1, 2, 3, 5 and 6) includes an inclined table 207 for slidably supporting a pack of sheets on edge, also a post 208 on which 65 said table 207 is swingably mounted, said post being swiveled in vertically spaced bearings 209 formed integrally with the gear guard 190. Provided at the side of the table 207, opposite the post 208, are legs 210 which, in the normal position of said table, rest upon a bracket 211 formed integrally with the side frame 31 of the unit. Further included in the stock feeding magazine A is a sliding back rest 212 for advancing a pack 70 of sheets on the table 207 and a gauge 213 for 75

regulating the advancement of the pack and thus maintaining the foremost sheet thereof in the desired sheet receiving position at the head of the magazine. A rocker-disk 214, employed in 5 actuating said back rest 212 and gauge 213, is rocked by means of an upright reciprocating rod 215 which is connected at its upper end with said rocker-disk 214 and at its lower end with a collar 216 (Figs. 3 and 8) mounted to slide, but 10 secured against turning on the post 208. This collar 216 turns with the post 208 within a second collar 217 mounted on said first collar, said second collar being deprived of angular movement and of sliding movement relative to the first 15 collar and serving, upon being elevated and lowered, to operate, through collar 216, the reciprocating link 215. For reciprocating the said swiveling collar assembly on the post 208, we employ a link 218 (Fig. 1) which is connected at 20 its upper end with the collar 217 and at its lower end with a lever 219. This lever 219 and others as well, operated by the cam assembly, as will more fully hereinafter appear, has a bearing 220 mounted on a lever shaft 221 supported in bosses 25 222 on the side frames 30, 31, the connection between the link 218 and said lever 219 being made through a lug 223 issuing from the bearing 220 of said lever.

At the head of the magazine A, beneath the 30 table 207 thereof, is an air exhaust pipe 224. A nipple 225 (Fig. 5) issuing upwardly from said pipe 224 discharges blasts of air through an opening in said table and between the lower edges of the leading sheets of the pack supported 35 upon the table. A valved hose 226 connects said pipe 224 with the exhaust outlet of a suction pump 227 of conventional construction, the piston rod 228 of the pump being connected with a crank 229 on the fly wheel shaft 33 and the body 40 of said pump being pivotally supported on a beam 230 carried at its ends by the side frames 30, 31.

The sheet feeding mechanism B is generally of the construction disclosed in Letters Patent of the United States Nos. 1,472,656 and 1,592,635 45 which matured from applications filed by us, the same being more especially like that of Patent 1,592,635 in the detailed construction of the head member. This feeding mechanism includes an oscillating feed arm 231 having suction grips 232 thereon which take the foremost sheet from the magazine and carry it edge foremost to the platen 39, placing said sheet upon the tympan sheet 375 (Fig. 6) with its leading edge against or near the lower gauges 375, in whatever position 50 said gauges may occupy on the tympan, and with the margin of said sheet at said edge in engagement with a bottom register tongue 377 (Figs. 5 and 6), if such a tongue is employed. Further included in the feeding mechanism B is 55 a tubular standard 233 (Fig. 1) mounted at the right side of the unit in bearings 234 formed integrally with the gear guard 198. Supported at the upper end of the standard 233 and extending inwardly over the bed 44 is a horizontally disposed head bearing 235 in which an eccentric bushing 236 is rockably mounted, the same being provided at its outer end with a rocker-disk 237. Mounted in said bushing 236 is a rock shaft 238 which at its inner end carries the feed arm 231 60 and to the outer end of which is secured a rocker arm 240. A rod 241 connects the rocker-disk 237 with the free end of a lever 242, while a similar rod 243 connects the rocker-arm 240 with the free end of the lever 219. These levers 219 65 and 242 are operated, respectively, by the cams

203 and 202 of the cam assembly, each lever having a roller, as at 244, which rides its respective cam. Through cam 203, lever 219, rod 243, and rocker-arm 240, the feed arm 231 is oscillated in accord with the rocking movement of the platen, whereby a sheet from the magazine is fed to the platen each time it opens, the suction grips 232 and feed arm 231 safely clearing the platen 39 in the co-ordinated cycles of movement of feed arm and platen. Through cam 202, 10 lever 242, rod 241, and eccentric bushing 236, the rock-shaft 238 is shifted to increase and diminish the reach of the feed arm 231 for facilitating the taking of sheets from the magazine A and the placing of sheets on the platen 39 and 15 the clearing of the platen and suction grips 232 during the oscillating movements of said feed arm 231 and platen 39. Suction is created in the grips 232, by means of the pump 227, said pump being connected at its suction side with 20 said grips through a tube 245, pipe 246, the tubular standard 233, the hollow feed arm 231, a tube 247 connecting the hollow standard 233 with the hollow feed arm 231, and tubes 248 leading from the grips 232 to said feed arm 231, said pipe 246 25 being fitted with a valve 249, actuated through rod 250, arm 251 and rod 252, for manually cutting off suction in the line to said suction grips 232. The tube 247 takes off from the hollow standard 233 above a self-seating ball valve (not 30 shown) for obstructing and clearing the passageway in said standard and beneath a self-seating ball valve 253 (Fig. 2) for admitting and barring the entrance of air to said passageway. These ball valves are unseated by a lever 254 35 (Fig. 1), which is automatically actuated to effect suction at the grips 232 in the sheet receiving position thereof and to destroy such suction in the selected sheet depositing position of said grips. No claim being made herein to the 40 said valves or their actuating mechanism per se, we have not deemed it necessary to illustrate and describe the same in detail, particularly in view of the disclosure in Patent No. 1,592,635.

As the bed 44 assumes printing position (Fig. 45 3), its superstructure, including the rails 54 and ink plate 57, swings forward toward the sheet magazine A, passing closely beneath the head bearing 235 of the feeding mechanism B into a position over the center of the machine, the feed 50 arm 231 being formed with a bend therein to clear said superstructure. This relation of said parts contributes to the compactness and to the balancing of the unit.

Means are provided for automatically throwing 55 off the printing unit and thus preventing the taking of an impression when the suction grips 232 fail to grasp a sheet at the magazine A, such means including a piston 255 (Fig. 8) in the standard 233 and a train of connections, now to 60 be described, which act upon the throw-off lever 23. Pivoted between its ends on a bracket 256 issuing from the side frame 30, is a lever 257 having a weight 258 attached to its forward end, said weighted end of said lever being connected 65 through a connecting rod 259 with the piston 255 and normally held against being swung downward by the sustaining action of said piston. The rear end of the lever 257 is connected through a link 260 with an arm 261 on a rock-shaft 262 70 mounted transversely of the legs 46 of the bed 44 in bearings secured to said legs, the connection between the link 260 and lever 257 being coincident with the axis of the bed shaft 47 in the normal position of said lever 257. On the rock- 75

shaft 262 is a second arm 263 (Fig. 3) having a pin 264 at the end thereof normally freely movable back and forth in a slot 265 cut in a link 266 which forms a connecting element between the bed 44 and the throw-off lever 93. This link 266 has a second slot 267 therein and is notched upwardly as at 268 (Fig. 2), between the ends thereof to receive a pin 269 (Fig. 3) in the throw-off lever 93, said pin serving to support the forward end of said link 266 and, when normally engaged in said notch 268, serving to pivotally connect said link 266 with said lever 93. Supporting the rear end of the link 266 is a flanged stud 270 which is secured to a leg 46 of the bed 44 and which normally slides back and forth beneath said link 266. When suction in the hollow standard 233 is impaired, as by the failure of the suction grips 232 to grasp a sheet at the magazine A, or, as by the closing of the valve 249 in pipe 246, the piston 255 in standard 233 fails to support the weighted end of the lever 257, with the result that said lever 257 acts to turn the rock-shaft 262 and swing the arm 263 so that the pin 264 on said arm enters a notch 271 cut downwardly in link 266 at the rear end of the slot 265 along which said pin normally freely passes. With said pin 264 engaged in said notch 271, the link 266 is moved with the bed 44 and, in turn, imparts such movement to the throw-off lever 93 through which the previously described throw-off mechanism is operated to turn the back shaft 49 and prevent the taking of an impression. Carried by the throw-off lever 93 is a trip rod 272, the same being connected at its upper end with a hand piece 273. The lower end of said rod 272 is bent inward providing a finger 274 which extends through a slot 275 in said lever 93 and beneath the link 266. Upon operating the hand piece 273 and thereby lifting the trip rod 272, said finger 274 engages and lifts the link 266 so that the pin 269 in the lever 93 occupies position in the slot 267 in said link rather than in the notch 268 branching upwardly from said slot. With the link 266 thus elevated by the trip rod 272, the connection between said link and the throw-off lever 93 becomes a sliding connection rather than a pivotal connection with the result that the link 266 reciprocates independently of the hand lever 93. The hand lever 93 being thus free from the link 266, it may be operated at will to throw on or throw off the impression.

The construction of the delivery mechanism C is somewhat the same as that of the sheet delivering device disclosed in Letters Patent of the United States No. 1,621,547 which matured from an application filed by us. It includes a track 276, consisting of parallel rails, (Figs. 1, 3 and 5) situated beneath the stock magazine A, said track being pivoted, as at 277, to a bracket 278 extending forwardly from the side frame 39. Mounted to reciprocate on this track toward and from the platen 39, is a carriage 279 having secured thereto a supporting bar 280, said bar being mounted on said carriage at an angle corresponding with the angle assumed by the platen 39 in its open position. A clamp 281 (Fig. 1), adjustable toward and from the platen 39 along this supporting bar 280, carries a tubular support 282. A grip mounting 283, carrying suction grips 284 slidably adjustable thereon, is adjustably clamped to the tubular support 282, said grips 284 being connected through tubes 285 with said tubular support 282 and said support being connected through a suction tube 286, pipe 287 and tube 288 (Fig. 5) with the suction side of the pump 227.

The carriage 279 is reciprocated on the track 276 by a cam lever 289 issuing from a boss 290 mounted on the lever shaft 221, said cam lever 289 being provided with a cam roller 291 which rides upon the cam 201. Issuing upwardly from said boss 290 is a lever 292, the same being connected at its upper end, through a link 293, with the carriage 279. The track rails 276 are oscillated on pivot 277 so that the delivery grips 284, in their cycle of movement, will follow a path substantially as follows: In approaching the platen, the grips 284 move substantially horizontally due to the then substantially horizontal position of the rails 276 (Fig. 5). Upon entering over the platen, the grips pitch sharply downward to sheet taking position, the descent thereof being caused by the downward swinging movement of the rails 276. In returning with the grasped sheet, said delivery grips 284 first travel substantially parallel with the inclined platen, due to the upward swinging movement of the rails 276 combined with the retracting movement of the grip support on said rails. After passing the platen, the grips 284 again travel substantially horizontally. Included in mechanism for oscillating said track 276 is a cam lever 294 (Fig. 8) mounted on a stub shaft 295 issuing from the side frame 39. One end of this cam lever 294 is provided with a cam roller 296, which bears against the cam 200. The other end of said lever 294 is pivotally connected through a rod 297 with the rear ends of the track rails 276 which are guided vertically between side plates of a guide 199. A valve structure 288 (Figs. 3 and 5) associated with the suction pipe 287 admits air to said pipe for the purpose of destroying suction in the delivery grips 284 at the sheet depositing positions thereof and bars the entry of air to said pipe 287 to reestablish suction at the grips 284 in the sheet taking positions thereof. This valve structure, not herein illustrated in detail or claimed per se, but which, as to its essentials, is disclosed in Patent No. 1,621,547, said valve structure being operated by a hinged lever 299 (Fig. 5), which, in turn, is operated by the lever 294 with which the track oscillating rod 297 is connected.

Constant contact between cam roller 296 (Fig. 8) and cam 200 is maintained through the medium of a tension spring 300 stretched between the cam lever 294 and an anchoring stud 301 issuing from the side frame 39, said spring 300 serving further to augment gravity in swinging the track 276 downward. The cam rollers 244 of the cam levers 219 and 242 and the cam roller 291 of the cam lever 289 are respectively maintained in contact with the cams 203, 202 and 201, by means of expansion springs 302 (Fig. 8). Each of said cam levers is integrally formed with a depending arm 303 having a socket therein in which one end of a rod 304 is received, the other end of said rod being slidably supported in a lug 305 issuing from the bracket 256. Encircling each of these rods 304 is one of said expansion springs 302, each spring abutting against the lug 305 at one end and at its other end against a washer 306 fixed to its respective rod 304. Thus, the springs 302, operating through the arms 303 and the cam levers 219, 242 and 289, yieldingly hold said cam rollers 244 and 291 in contact with their said respective cams 203, 202 and 201.

The movements of the platen 39, feed arm 231 and delivery grips 284 are co-ordinated so that said feed arm and delivery grips do not interfere with each other or with the platen. The platen dwell is comparatively short to promote speed of 75

operation, the movements of the feed arm 231 and delivery grips 284 in their respective cycles of operation being regulated to accord with the platen movements and with workmanlike design 5 in the construction of operating parts.

Grippers 307 hold a printed sheet against the face of the opening platen in the position in which it was printed on the platen. During that part of the platen cycle, when the platen is in or 10 near its fully open position, the delivery grips 284 advance over the platen to grasp the printed sheet at predetermined localities thereon in the predetermined printing position thereon on said platen. At the same time, the grippers 307 swing 15 away from the face of the platen to free the printed sheet to said delivery grips. It will be understood, therefore, that said grippers 307 secure the printed sheet flatly against the platen, keeping said sheet from curling or from being 20 otherwise displaced from printing position on the platen, as by the rapid opening movement of said platen, or, as by the movement of the side register gauge in its return to starting position. With the printed sheet thus held against the face 25 of the opening platen, in the position thereon in which it was printed, it is properly directed into the range of the delivery grips 284 and, with said grips properly adjusted to contact only with uninked portions of the sheet in such position on 30 the platen, the smearing of ink on the sheet is avoided. In this connection, it is also to be noted that the grippers 307 hold the printed sheet flatly against the platen until the delivery grips 284 pass over the sheet. Thus, there can be no danger 35 of the grips 284 passing under the printed sheet or colliding with it during the advancement of said grips into sheet grasping position.

Said grippers 307 are secured to a gripper bar 308 (Fig. 5) pivoted at its ends in the bearings 383, 184 (Fig. 2) which support the side register rod 182. A roller arm 309 issuing from said gripper bar 308 carries a roller 310 which rides upon an arcuate cam 311, (Fig. 6). Said cam 311 is supported at its lower end by the lower end 45 of a lever 312 pivoted on a stud 313 issuing from the side frame 31, the upper end of said lever carrying a roller 314 which bears against a cam 315 (Fig. 6) secured to the inner face of the crank wheel 52. A coiled spring 316 (Fig. 2), stretched 50 between the roller arm 309 and the platen 39, keeps the roller 314 in contact with the arcuate cam 311, and, through said cam 311 and lever 312, keeps the roller 314 on lever 312 in contact with the cam 315. When the roller 314 bears upon the 55 uniform high side of the cam 315, the roller engaging surface of the arcuate cam 311 coincides with an arc struck from the axis of the platen rocker trunnions. In this position of said arcuate cam 311, the grippers 307 are held closed against the platen 39 during the opening movement thereof. As the roller 314 rides onto the low side of 60 cam 315, the grippers 307 are opened, their opening movement first releasing the printed sheet on the open platen to the delivery grips 284 and 65 then receding to keep clear of the feed grips 232.

As the platen 39 closes and said roller 314 rides further along the cam 315, the grippers 307 close upon the newly fed sheet on the platen 39.

A delivery table 317 supports the printed sheets 70 as they are dropped one by one from the delivery grips 284 of the sheet delivery mechanism and accumulate in a pile. This delivery table 317 is lowered automatically in such manner that the uppermost of the sheets accumulated in the pile 75 always occupies position substantially in a given

plane. Said table 317 is supported on a post 318 slidably mounted in a post bearing 319 formed integrally with a horizontal bracket 320 bolted to and extending forwardly from the side frames 30, 31. Teeth cut in this post 318 form a rack 5 which meshes with a gear 322 (Fig. 5) on a shaft 323, said shaft being journaled in the post bearing 319 and in a bearing 324 issuing upwardly from said horizontal bracket 320. The shaft 323 may be turned in either direction by 10 means of a handle 325 thereon to elevate or lower the delivery table 317 at will, the self-lowering of said table, being prevented by frictional means including collars 326 and 327 and a coiled spring 328 (Fig. 23). The collar 326 is fixed to the shaft 15 323 and collar 327 loosely mounted thereon, said spring 328 being compressed between the two collars. This spring 328 yieldingly, frictionally engages the collar 327 with the side of the bearing 324 and sets up sufficient frictional resistance 20 against the turning of the shaft 323 to keep the delivery table 317 from descending by reason of its own weight or the added weight of stock piled thereon. For automatically lowering the table 25 to compensate for the accumulation of the delivered printed sheets, the shaft 323 is turned step-by-step in a counter-clockwise direction as seen in Figs. 21 and 22, a ratcheting drive mechanism being employed to thus turn said shaft. Said mechanism includes a ratchet wheel 329 30 fixed to the shaft 323 and a bell-crank 330 rockably mounted thereon, said bell-crank including arms 331 and 332, the arm 331 carrying a pivoted pawl 333 which, by gravity, engages with the ratchet wheel 329, the arm 332 being connected 35 through a link 334 with a bell-crank 60 on the unit master shaft 61. This link 334, operated by the bell-crank 60 upon each cycle of the printing unit, in turn, operates the bell-crank 330 causing the shaft 323 to be turned a step, through 40 the cooperation of the pawl 333 and ratchet wheel 329. The teeth of the ratchet wheel 329 are so proportioned in respect to the working throw of the pawl 333 that said pawl normally turns the ratchet wheel one tooth at a time. At times, however, the pawl 333 is rendered inoperative, by 45 mechanism soon to be described, whereby the lowering of the delivery table 317 is intermittently interrupted, through one or more cycles of the printing unit, to accord with the thinner 50 stocks of paper and thus, under all conditions, maintain substantially in a given plane the uppermost sheet of the pile on the delivery table. The sheets of a pile on the delivery table 317 55 are maintained in place thereon by means of two adjustable side guides 335 and an adjustable back guide 336. The side guides 335 are similar in construction, each consisting of an upright guide-bar formed at the lower end thereof with a pair of spaced bearings which are slidably adjustable 60 along horizontally disposed rails 337 mounted on the bracket 320. These side guides 335 are freely received in slots 338 in the table 317, said slots being formed, as best seen in Fig. 2, and extending inwardly from opposite sides of the 65 table well toward the middle thereof. The back guide 336 constitutes a rack-like structure consisting of a plurality of upright guide-rods 339 interconnected at their upper ends by tie bars 340 and secured at their lower ends in a base bar 70 341 slidably supported on edge upon tracks 342 (Figs. 5 and 6) formed on the bracket 320. These guide-rods 339 are freely received in slots 343 formed in the delivery table 317, the entire rack-like guide structure being shiftable back and 75

forth relative to the delivery table, whereby said structure may be stationed, as desired, in respect to said table. Holding said rack-like guide structure in upright position and providing for the 5 ready backward or forward adjustment thereof is a push-pull rod 344, one end portion thereof being frictionally, slidably mounted in the post bearing 319 and the opposite end portion thereof being similarly mounted in an upturned ear 345 10 (Fig. 6) formed integrally with the bracket 320. The end portions of said push-pull rod 344 are reduced, providing shoulders or limit stops 346 and 347, the former being adapted to engage the post bearing 319 and the latter being adapted to 15 engage said ear 345, whereby the guide rods 339 are kept clear of the table 317, at the ends of the slots 343 therein, and thus protected against strains that otherwise might be imposed upon them in the operation of the push-pull rod 344. 20 Supported on the intermediate rod 339 of the back guide is a gauge 348 through which the action of the pawl 333 is controlled and the lowering of the delivery table 317 regulated. The body of this gauge consists of a sleeve slidably mounted 25 on said intermediate rod 339, said sleeve having a head 349 formed with a beveled face 350 for directing a falling sheet to the table 317 into such position thereon that, upon settling, it will be marginally disposed beneath a shoulder 351 (Fig. 30 22) also formed on said head 349. This gauge 348 is lifted into an elevated position upon each cycle of the printing unit, being stationed in such elevated position at the time a printed sheet is dropped by the delivery grips 284 to the pack 35 on the delivery table. Thereafter, the gauge 348 descends by gravity, the shoulder 351 thereof engaging the uppermost sheet of the pack and arresting the descent of said gauge in the event that said sheet lies above the predetermined 40 plane of delivery. Otherwise, the gauge 348 descends to the lowermost limit thereof at which limit said shoulder 351 occupies a position substantially coincident with said predetermined plane of delivery. In this connection, it may be 45 stated that the gauge 348 upon being arrested in its descent substantially short of its lowermost limit will have no effect upon the normal operation of the pawl 333 and the consequent lowering of the delivery table. But, it will be understood 50 that when the gauge 348 does not encounter the pack and is allowed to descend to its lowermost limit, it will serve to render the pawl 333 inoperative and thus preclude, in that particular cycle of operation, the further lowering of the delivery 55 table. The operating train between the gauge 348 and ratchet 329, best shown in Figs. 2, 21 and 22, includes a shaft 352 journaled on the side frames 30, 31, said shaft having an arm 353 and a bell-crank 354 fixed thereto and an arm 355 60 loosely mounted thereon. The extreme end portion of the arm 353 is turned at right angles to the body thereof forming an ear 356 which is apertured loosely to receive a stem 357 projecting from a collar 358 secured to the lower end of the gauge 348. Arm 359 of the bell-crank 354 carries a weight 360 which, in part, counter-balances the weight of the gauge 348, the other arm 361 of said bell-crank being disposed so as to engage a stop pin 362 projecting from the loosely 65 mounted arm 355. This loosely mounted arm 355 is connected through a link 363 with the arm 332 of the bell-crank 330 upon which the pawl 333 is mounted. A trip rod 364 pivotally connected at one end to the arm 361 of bell-crank 70 330 is slidably supported near its other end in a 75

clip 365 (Fig. 23) secured to the bracket 324. Adjustably fixed at the extremity of said trip rod 364 is a trip finger 366 which at times engages a trip lug 367 on the pawl 333. Upon the forward throw of the arm 332 (to the right from the position shown in Figs. 21 and 22), the pin 362 on arm 355 engages arm 331 of the bell-crank 354 and, through shaft 352, arm 353 and stem 351, elevates the gauge 348 to receive beneath the shoulder 351 thereof the sheet being then delivered. Upon the rearward throw of the arm 332 to the position shown in Figs. 21 and 22, the arm 361 of bell-crank 354 follows the pin 362 on arm 355 to the end of the rearward stroke of said arm 332 (Fig. 22) or to a point short thereof should it be that the descent of the gauge 348 is arrested by the pile (Fig. 21). When the position of the uppermost sheet of the pile is such that the descent of the gauge is not arrested thereby and the arm 361 follows through to the end of the rearward stroke of the arm 355 (Fig. 22), the trip finger 366 engages trip lug 367 of the pawl 333 and tilts said pawl from engagement with the ratchet 329. When said trip finger 366 engages the trip lug 367 at the beginning of the forward stroke of the arm 332 and holds the pawl 333 inoperatively tilted, said pawl is caused to clear the shoulder of the tooth of ratchet 329 which otherwise would be engaged thereby, with the result that the said forward stroke of said arm 332 is without effect in so far as the turning of shaft 323, through the ratchet 329, is concerned. But, unless the trip finger 366 is so positioned with respect to the trip lug 367 as to fully unseat the pawl 333 from the ratchet wheel 329, the forward throw of the arm 332 will effect the turning of the table lowering shaft 323 through said pawl 333 and ratchet wheel 329. When the delivery table 317 reaches the last stage of its descending movement, the operation of the ratcheting mechanism is automatically interrupted to limit the lowering of said table and thereby prevent the accidental breakage of parts. Mounted on the table 317 is a trip-latch 368 consisting of a bar which is pivoted at one end thereof on a pivot screw 369 threaded in said table. This bar 368 is formed with a slot 370 laterally hereof, said slot freely receiving a limit screw 371 also threaded in said table 317. The free end of said trip-latch 368 either drops in back of the trip-lug 367 on pawl 333 (dotted lines, Fig. 22) or bears on the upper edge of said trip-lug, as the case may be, depending upon the position occupied by the pawl 333 when the trip-latch 368 comes within operating range thereof. If said latch 368 first takes position in back of the trip-lug 367, the pawl 333, being then in inoperative position, is thereupon immediately barred against tilting into engagement with the ratchet wheel 329. However, if the free end of the trip-latch 368 comes to bear upon the upper edge of the trip-lug 367, the pawl 333 being then in engagement with the ratchet wheel 329, said latch will pivot on the pivot screw 369 until the pawl 333 again tilted into its inoperative position, whereupon the trip-latch 368 will then drop in back of the latter lug 367 and hold said pawl inoperative. Applied to the arm 331 of bell crank 354 is a spring pressed ball-stop 372 (Fig. 23) beyond which the lower end of the trip-lug 367, on pawl 333, may be swung by hand. This ball-stop 372 serves, through said trip-lug 367, to hold the pawl 333 in tilted, inoperative position and thus provides for readily discontinuing the auto-

matic lowering of the delivery table 317, at will, at any stage in the descent of said table.

From the foregoing, it will be understood that the feed grips 232 have control of a sheet as it is fed from the magazine A to the platen gauges 315, which gauges have control of the sheet from the time it is released by said feed grips 232 until the impression takes place; that the grippers 307 have control of the printed sheet on the opening 10 platen until the delivery grips 284 are in a position to grasp said sheet and take over the control thereof; and that said delivery grips carry the printed sheet under control from the platen to the point of discharge above the delivery 15 table 317.

Changes in the specific form of our invention, as herein disclosed, may be made within the scope of what is claimed without departing from the spirit of our invention.

Having described our invention, what we claim 20 as new and desire to protect by Letters Patent is:

1. In a printing unit, a frame, a bed, an ink 25 roller carriage mounted on the bed, a platen, a platen rocker supporting the platen and trunnioned on said frame, a master shaft in the frame, means for feeding sheets to the platen, means for taking sheets from the platen and means for moving said carriage on said bed, 30 all of said means having parts thereof mounted on said master shaft, means for oscillating the platen rocker, a rocker lock pivoted on the frame, means actuated through said master shaft for swinging said rocker lock into and out of locking 35 position, said last mentioned means including a cam on said master shaft and a cam arm on said rocker lock cooperating with said cam, and means, operating through said master shaft, to counterbalance said ink roller carriage, said 40 counterbalancing means including a member connected with said cam, the cam serving as an operating arm for said member.

2. In a printing unit, a frame, a bed, an ink 45 roller carriage mounted on the bed, a platen, a platen rocker supporting the platen and trunnioned on said frame, a master shaft in the frame, means for feeding sheets to the platen, means for taking sheets from the platen, and means for moving said carriage on said bed, all of said 50 means having parts thereof mounted on said master shaft, means for oscillating the platen rocker, a rocker lock pivoted on the frame, and means actuated through said master shaft for swinging said rocker lock into and out of locking 55 position.

3. In a unit comprising mechanisms for automatically printing sheets, a frame, a platen, a bed pivoted on the frame and adapted to receive a form from which impressions are to be taken, 60 means for rocking the bed toward and from the platen, rails at opposite sides of the bed paralleling the plane of the form, an inking carriage reciprocably mounted on said rails, a master shaft in the frame, mechanism for reciprocating 65 the carriage on the bed, said mechanism and others having said master shaft as a common element, said carriage reciprocating mechanism consisting of bell-cranks mounted on the master shaft at opposite sides of the frame, connecting 70 rods, one for each bell-crank, said rods connecting said bell-cranks with the bed, links, one for each bell-crank, said links connecting said bell-cranks with the carriage, the axis of the master shaft and the axis of the bed being disposed to 75 vide for the constant disposition of the connec-

tions between said bell-cranks and links substantially in the reciprocal plane of the roller carriage.

4. In a unit comprising mechanisms for automatically printing sheets, a frame, a platen, a bed pivoted on the frame and adapted to receive a form from which impressions are to be taken, means for rocking the bed toward and from the platen into and out of printing position, an inking carriage mounted to reciprocate on the 10 bed, a master shaft mounted in the frame, means for reciprocating the carriage, said means comprising a bell-crank on the master shaft, a rod connecting one arm of the bell-crank with the bed, a link connecting the other arm of said 15 bell-crank with said carriage, means for counterbalancing the weight of the carriage through said link and bell-crank, the master shaft constituting an element of said counterbalancing means and of other mechanisms of the unit. 20

5. In a printing unit, a frame, a bed, an inking carriage reciprocably mounted on the bed, a platen rocker mounted on the frame and having a platen thereon, means for oscillating said platen rocker, means for rocking the bed toward and from the platen, a master shaft rockably mounted in the frame, a bell-crank fixed to said shaft, a rod connecting one arm of the bell-crank with the rocking bed, a link connecting the other arm of said bell-crank with said carriage, a rocker lock pivoted on the frame, a cam arm on the rocker lock, compression means for counterbalancing the weight of the inking carriage, and a cam on the master shaft cooperating with said cam arm and with said compression means. 30

6. In a printing unit, a frame, a rocking bed, an inking carriage reciprocably mounted on the bed, an oscillating platen, locking means for the platen, means operated by the bed for reciprocating the carriage thereon, said means including a rocker member mounted on the frame, means for counterbalancing the weight of the inking carriage, said platen locking means being operated by said rocker member, said member constituting an element of said counterbalancing means. 40

7. In a printing unit, a frame, a rocking bed, an inking carriage reciprocably mounted on the bed, an oscillating platen, a master shaft in the frame, locking means for the platen, means operated by the bed for reciprocating the carriage 50 thereon, a sheet magazine having a pack advancing means for advancing sheets therein, means for feeding sheets from the magazine to platen, and means for delivering printed sheets from the platen, each of said platen locking means, carriage reciprocating means, pack advancing means, sheet feeding means and sheet delivering means having said master shaft as an element thereof. 55

8. In a printing unit, a frame, a rocking bed, an inking carriage reciprocably mounted on the bed, an oscillating platen, a master shaft in the frame, means operated by the bed for reciprocating the carriage thereon, means for feeding sheets to platen, and means for delivering printed sheets 60 from the platen, each of said carriage reciprocating means, sheet feeding means and sheet delivering means having said master shaft as an element thereof. 65

9. In a printing unit, a frame, a rocking bed, an inking carriage reciprocably mounted on the bed, an oscillating platen, a master shaft in the frame, locking means for the platen, and means operated by the bed for reciprocating the carriage 70 thereon, each of said platen locking means and 75

carriage reciprocating means having said master shaft as an element thereof.

10. In a machine of the character described, a frame, a platen, a bed pivoted on the frame and adapted to receive a form from which impressions are to be taken, means for rocking the bed toward and from the platen into and out of printing position, an inking carriage mounted to reciprocate on the bed substantially in the plane of the form, means for reciprocating the inking carriage, said means comprising a lever pivoted on the frame, a link connecting said lever with said roller carriage, and means operated by the rocking bed for swinging said lever, the disposition of said lever being such that said link is constantly disposed substantially in the plane of reciprocation of said carriage, whereby side thrusts on the carriage are effectually minimized.

11. In a printing unit, a bed, a platen, means for imparting to the platen a cycle of movement wherein at one part thereof, the platen is in closed printing position and at another part

thereof is in or near fully open position, a delivery grip movable to take sheets from the platen during said latter part of the platen cycle, a registering device for side registering a sheet on the platen, said device including a member mounted on the platen, a gripper for holding a printed sheet on the opening platen until it reaches said latter part of the platen cycle, independent means for moving said delivery grip, gripper and register member, the means for moving said register member operating coextensively with the closing movement of the platen to shift a sheet into position of register and coextensively with the opening movement of the platen between said first and second parts of its cycle to retract said member, the gripper moving means operating to release the printed sheet after the retraction of the side register member and before the removal of said sheet is initiated by the delivery grip.
